Patented Jan. 18, 1921.

UNITED STATES PATENT OFFICE.

OCTAVER S. PAYZANT, OF NEW YORK, N. Y.

INTERLINE-TICKET GUIDE.

1,366,276.

Specification of Letters Patent. Patented Jan. 18, 1921.

Application filed April 10, 1920. Serial No. 372,837.

To all whom it may concern:

Be it known that I, OCTAVER S. PAYZANT, a citizen of the United States, and a resident of the city of New York, borough of Manhattan, in the county and State of New York, have invented a new and useful Interline-Ticket Guide, of which the following is a full, clear and exact description.

This invention relates to ticket cabinets and guides therefor and has for an object the provision of an improved construction for use in what is known as interline tickets whereby the tickets are always held in proper place while maintained in position for quick and easy removal.

Another object of the invention is to provide a guide for ticket cabinets which may be easily applied and removed and which is applicable for use with any quantity of tickets.

A still further object of the invention is to provide a guide for ticket cases adapted to be placed on top of a stack of tickets for holding the tickets in place and permitting removal of only one ticket at a time.

In the accompanying drawing:

Figure 1 is a fragmentary front view of a ticket cabinet and a guide embodying the invention.

Fig. 2 is an enlarged sectional view through Fig. 1 approximately on line 2—2.

Fig. 3 is a horizontal sectional view through Fig. 2 on line 3—3.

Fig. 4 is a perspective view of a guide embodying the invention.

Referring to the accompanying drawing by numerals, 1 indicates a cabinet of any desired description, which is provided with vertical compartments 2. Each side wall of each vertical compartment is provided with a groove 3, while a plurality of openings 4 are provided in the rear wall. The cabinet may be made from wood, though preferably it is constructed of metal, as shown in Fig. 3, wherein the grooves 3 are provided by bending the metal sheets and the openings 4 in the rear of each compartment 2 are provided by pressing out sections 5.

In the various compartments 2 are arranged adjustable shelves 6 for receiving the tickets 7, said shelves having bent out depending portions 8 adapted to be insert-

ed through any of the openings 4. In addition the shelves 6 are provided with depending flanges 9 which act as supporting braces. On any shelf 6 may be arranged any number of tickets 7, which tickets may be cardboard, folded tickets, or any desired form of ticket. To hold the bunch of tickets in a reasonably compact condition a guide 10 is provided. This guide is formed with pressed out portions 11 and 12 designed to fit into the notches 3 on opposite walls of the compartment and to press somewhat against the side walls of the compartment for resisting sliding movement.

The guide 10 is made principally from a single piece of metal, stamped out and formed up into the desired shape, though a few additional separate members have been connected to the stamping, same including a guard lip 13, a spring 14 and a shaft 15 journaled in the finger holds or extensions 16 and 17. These finger holds merge into the pressed out portions 11 and 12, which in turn merge into side members 18 and 19 adapted to fit flatwise against the side walls of the compartment, while said side members merge into diagonally arranged sections 20 and 21 connected by a rear section 22. The sections 20 and 21 are provided with bottom flanges 23 and 24 bent up at one end for forming return guides 25 and 26 for guiding a ticket back into place when it is desired to replace any ticket. A depending reinforcing member 27 projects from the end 22 and is folded over the rear part of the flanges 23 and 24 so as to reinforce the device at this point. It will be noted that the finger holds 16 and 17 are cut at 28 so that there will be provided independent front projections 16' and 17' for receiving the rod 15, said projections being overlapped by the end flaps 29 of the guard lip 13. This arrangement permits the hand holds 16 and 17 to have a slight resilient action, which resilient action is assisted by the resiliency of the sides 18 and 19, whereby when it is desired to remove the guide from the position shown in Fig. 3 the hand holds 16 and 17 are grasped and pressed toward each other until the pressed out portions leave the grooves 3 whereupon the guide 10 may be moved completely out of the compartment 2.

In replacing the guide a reverse action is performed. After the guide has been replaced the fingers of the operator are pressed on the flanges 23 and 24 until the guide compresses somewhat the tickets 7. The parts are then left in this position as the guide is in full operative condition at this time. When it is desired to remove a ticket the finger of the operator is inserted and placed 10 on top of the ticket between the flanges 23 and 24; after the finger has been placed in this position it is pulled forwardly so that the upper ticket will move from the stack of tickets and strike against the guard lip 13 over which it will move as shown in Fig. 2. In case the ticket is an interline ticket, and is consequently comparatively thick, this guard lip will yield under the pressure of the ticket and will wind the spring 14 somewhat. After the ticket has been removed 20 the guard lip 13 will assume its former position. The guard lip 13 may be mounted on the shaft 15 in any desired manner, as for instance by having part thereof pressed out 25 so as to form knuckles 30 and 31.

By this construction and arrangement of guide and shelf 6 and associate parts, any desired number of tickets may be arranged in any compartment 2, as for instance a 30 large number of small packs with a guide and shelf for each pack, or only one guide and one shelf for a large number of tickets. It will also be noted that by the arrangement of the guide lips 25 and 26 a ticket accidentally removed, or one which a 35 customer refuses to take for any reason may be easily replaced.

What I claim is:

1. A guide for ticket cases comprising a 40 frame having a resilient front end, a resilient guard lip extending across the front, and means for guiding the return of a ticket to a position beneath the guide.

2. A cabinet and ticket guide comprising 45 a casing formed with a plurality of vertical compartments, each compartment having a pair of grooves, a guard positioned in each compartment formed with a resilient front extension having a pressed out portion 50 adapted to fit in said grooves, and means for causing only the top ticket to be removed at a single operation.

3. A ticket guide comprising a frame formed with a pair of resilient front members, each of said front members being provided with a bent out guide portion adapted to engage a cabinet, and a spring pressed guard lip extending across the front of said frame.

60 4. A ticket guide for use in holding tickets in cabinets comprising a body formed with inwardly extending flanges at the rear part, each of said flanges having a bent up front end so as to guide tickets 65 when being returned to a position beneath

the flanges, and a guard lip arranged at the front of the body for preventing more than one ticket being removed from beneath the body at one time.

5. A ticket guide for holding in place and 70 guiding the removal of tickets in cabinets, comprising a frame adapted to rest on a stack of tickets and hold the same normally in place, said frame being open at the center and at the front, means for holding 75 the frame in position in the cabinet, and a spring pressed guard lip arranged so that the upper edge will be approximately in line with the direction of travel of the ticket being removed from beneath the frame in a 80 direction toward the front of the cabinet and the guide.

6. A ticket guide for cabinets comprising a frame adapted to fit flatwise against a 85 stack of tickets in a cabinet, said frame having an opening in the bottom through which the fingers of the operator are passed when a ticket is to be removed, said frame being open at the front, a journal rod arranged in said opening, a guard lip pivotally mounted 90 on said rod, and a spring for resiliently holding said guard lip in a given position.

7. A ticket guide comprising a frame 95 comprising upstanding walls and flanges extending inwardly from the bottom of said walls, each of said walls being formed with a front extension having a resilient finger hold, said resilient finger hold being formed with pressed out retaining portions, and a guarding lip carried by the lower part of 100 the front portion of said walls.

8. A ticket guide comprising a body formed with a pair of side walls, a connecting rear wall and a plurality of bottom flanges, each of said side walls being formed 105 with an outwardly extending projection merging into resilient hand holds and rod receiving member, each of said hand holds being formed with retaining means adapted to automatically move into place when the 110 guide is in use and to be sprung to a different position when it is desired to remove the guide, and a yielding guard lip carried by the extensions on the front portion of said side walls, said guard lip acting to prevent 115 more than one ticket being removed at one time.

9. In a ticket guide of the character described, the combination with a cabinet having a pair of opposite grooves, of a shelf 120 removably connected with said cabinet for supporting a number of tickets, and a guard for said tickets formed with a resilient pressed out portion fitting into said grooves, said guard being formed with an opening 125 through which the fingers of an operator may extend so that by a downward and forward pull tickets may be removed from beneath the guide.

10. In a ticket guide of the character de- 130

scribed, the combination with a cabinet having a pair of opposite grooves, of a guide member adapted to rest on top of a stack of tickets in the cabinet, said guide member being formed with resilient forward extensions, each of said extensions having a pressed out bead for fitting into said

grooves so as to prevent accidental removal, a guard lip extending across the front of the guide member, and means arranged back 10 of the guard lip for guiding the tickets when they are being replaced.

OCTAVE S. PAYZANT.
